UNITED STATES PATENT OFFICE.

ALONZO E. RHOADES, OF HOPEDALE, MASSACHUSETTS, ASSIGNOR TO DRAPER CORPORATION, OF HOPEDALE, MASSACHUSETTS, A CORPORATION OF MAINE.

INTERMITTENT FEELER MECHANISM FOR LOOMS.

Application filed July 19, 1924. Serial No. 726,924.

To all whom it may concern:

Be it known that I, ALONZO E. RHOADES, a citizen of the United States, residing at Hopedale, in the county of Worcester and 5 State of Massachusetts, have invented an Improvement in Intermittent Feeler Mechanisms for Looms, of which the following description, in connection with the accompanying drawings, is a specification, like characters on the drawings representing like parts.

This invention relates to feeler mechanisms for looms and more particularly to feeler mechanisms of the intermittent type wherein the feeler is held in a position of 15 inactivity for periods of time and is released at intervals to its periods of activity.

One of the objects of the present invention is to provide a feeler mechanism of the intermittent type which shall be simple in construction and efficient in operation, and one 20 of the features of the invention consists in means for suspending the operation of the feeler trip mechanism during an active period of the feeler.

Another important feature of the present invention consists in means for removing the feeler to a position beyond the reach of the filling on detecting beats when it is in its inactive period.

The various novel features of the invention and new combination of parts will best be made clear from the following description and the accompanying drawings of one good practical form thereof.

In the drawings:

Fig. 1 is a perspective view of portions of the loom having the present invention applied thereto;

Fig. 2 is an enlarged detail showing more 40 particularly the feeler mechanism and its controlling means;

Fig. 3 is a side elevation of portions of the feeler controlling mechanism;

Fig. 4 is a section on the line 4—4 of 45 Fig. 3;

Fig. 5 is a plan view of the feeler mechanism showing the feeler as having been moved forwardly by a working supply of filling; and

Fig. 6 is a similar view showing the feeler 50 moved to its forward position beyond the reach of the filling.

The present invention is shown as associated with means for effecting replenishment

of filling when the feeler detects substantial 55 exhaustion of the filling in the shuttle, but the invention, of course, is not restricted in this respect, as the feeler mechanism may be employed in effecting other changes in loom operation. It has not been deemed necessary 60 to illustrate herein the replenishing mechanism because the details thereof form no part of the present invention.

In the illustrated form of the invention 65 the feeler is shown as of the inclined type, similar in this respect to the feeler mechanism shown and described in the patent to Edward S. Stimpson, No. 1,309,226, dated July 8, 1919, and while the advantages of 70 the present invention are well manifested in this type of feeler, the invention is not restricted thereto but may be employed with other types with equal advantage.

The loom frame 1 is of usual construction 75 and has mounted at the front thereof the transverse or rock shaft 2 supported in bearings 3, one at each side of the loom, and rising from the rock shaft 2 is an arm 4 to which is pivoted at 5 the rearwardly extending arm 6 to the rear end portion of which is 80 pivotally supported the finger 7 adapted at times to be moved frontwardly by the operating member or cam follower 8.

Mounted on the support 9 secured to the 85 loom frame is a bell crank lever, the horizontal arm 10 of which underlies the projection 11 on the finger 7. The bell crank lever is pivotally mounted at 12 and has its arm 13 connected to a transmitter 14 which is under control of the feeler, the construction being such that should the feeler detect substantial exhaustion of the filling on a detecting beat, it will lift the finger 7 into position to be operated by the operating member 8, as usual.

The feeler stand 15 may be adjustably secured to a bracket 16 mounted adjustably on an arm 17 extending from the shipper stand, and in the present instance the feeler stand 90 is held in its adjusted position by a bolt 18 which passes through a slot 19 in the feeler stand.

At the rear of the feeler stand is a slide 20 mounted for transverse movement in the rear bearing 21 and connected at 22 to the transmitter 14. The slide 20 is best shown in Figs. 5 and 6, and has a slot 23 through which the feeler 24 extends. The 105

frontwardly extending stem portion 25 of the feeler passes through a swivel block 26 mounted on the feeler stand, and interposed between the swivel block and a bridge or support 27 carried by the feeler is the usual feeler spring 28 normally acting to move the feeler into its feeling position.

The construction and operation of the train of mechanism thus far described may 10 be the same as that shown and described in the Stimpson patent, hereinbefore mentioned, although the invention is not restricted thereto.

The lay 29 is of the usual construction 15 and the feeler shuttle box 30 is provided with the usual opening 31 which registers with an opening 32 in the shuttle 33 when the latter is properly positioned in the feeler box.

20 In accordance with the present invention, the feeler is to be held in a frontward position during its period of inactivity and is to be released at intervals to its period of activity and, as shown, the feeler is held in 25 its frontward position by a holding device or detent during its periods of inactivity and is released by a trip mechanism at intervals to its periods of activity. The trip mechanism may be variously contrived, as 30 may also be the holding device or detent, but a good practical form of the invention in these respects comprises a ratchet wheel 34 which is given a step-by-step movement from a going part of the loom.

35 In the present instance the feeler stand has secured thereto a bracket 35 by means of a bolt 36 and extending from the bracket 35 is an arm 37 carrying a pin or shaft 38 on which the ratchet wheel 34 is mounted. 40 The ratchet wheel is supported to rotate in a plane substantially transverse to the longitudinal axis of the feeler and is stepped along by a pawl mechanism which will be hereinafter described.

45 Mounted on the pin or support 39 carried by the bracket 35 is the detent or holding member 40 which not only has rotative or rocking movement on the pin 39 but also a swinging movement towards and from 50 the front of the loom, the pivotal support or pin 39 being sufficiently loose in the detent or holding member 40 to permit both the pivotal and frontward rocking movement.

55 Mounted upon the feeler stem at the front thereof is a collar 41, Figs. 2 and 3, and the active end portion 42 of the detent or holding device 40 is adapted to engage the rear face 43 of the collar to maintain the feeler 60 in its frontward inoperative position. The collar may be conveniently secured adjustably to the feeler stem by means of a bolt 44.

The ratchet wheel 34 carries a trip lug 45, Figs. 2 and 4, which is adapted to engage a projection 46 extending from the de-

tent 40 to thereby lift the inactive end of the detent to free the feeler that it may move to feeling position.

The inactive end of the detent 40 is normally under the influence of a spring 47 tending to move the active end of the detent rearwardly, as indicated in Fig. 5. In the present instance the spring 47 is contained within a housing 48 and acts upon the plunger 49 that bears upon the inactive end portion of the detent and normally tends to move the detent into its inclined position, Fig. 5, with the active end 42 of the detent in a rearward position. The face of the plunger 49 is of sufficient extent to provide a bearing against the detent in its holding and releasing positions.

85 Mounted upon the face of the ratchet wheel 34 is a cam 50, Figs. 2 and 4, which has a cam riser 51 adjacent to but somewhat removed from the trip lug 45, as indicated in Figs. 2 and 4. The cam 50 extends about the face of the ratchet or trip wheel 34 and its end portions are adjacent to the trip lug 45.

90 Assuming that the ratchet 34 is being stepped along by a train of mechanism, the trip lug 45 will eventually rise beneath the lug 46 of the detent or holding device and move it upwardly, as indicated in Fig. 4, thereby freeing the feeler that it may move to feeling position during its periods of activity. When the feeler is in its feeling position, the active end portion 42 of the 100 detent 40 is engaged with the lower surface of the collar 41 secured to the feeler and is consequently held in its tripping or feeling position until when the feeler is moved frontwardly by a working supply of filling, the collar 41 will move sufficiently frontward to permit the active end 42 of the detent to engage rearwardly of the collar 41, as indicated in Figs. 2 and 5, and retain the feeler in a frontward position. When 105 the trip lug 45 has passed the projection 46, Fig. 4, and the feeler has been moved frontwardly as described, the spring 47 will throw the detent into its holding position behind the collar 41, the detent at such times being in the inclined position indicated by Fig. 5. As the ratchet wheel 34 is stepped along, the projection 46 will ride over the inclined portion 51 of the cam 50,

110 thereby swinging the active end of the detent 40 frontwardly from the position indicated in Fig. 5 to that of Fig. 6, and perforce will move the feeler 24 to a frontward position beyond the reach of the filling on subsequent detecting beats, and will maintain the feeler in this position during the rotative movement of the ratchet 34 by reason of the cam 50 extending about the face of the ratchet.

115 The ratchet wheel 34 is actuated from a train of mechanism which, in the present 120

instance, comprises the rocker arm 52 which may be conveniently mounted for rocking movement upon the stud 53. At its lower end the rocker 52 has a portion 54 which 5 embraces a cam 55 on a shaft 56 actuated through a train of mechanism from a going part of the loom, as, for instance, the under or cam shaft 57. The shaft 56 is shown as a take-up transmitting shaft by which the 10 take-up mechanism of the loom is actuated, but the present invention contemplates that the rocker arm 52 may be actuated from any suitable going part of the loom.

At its upper end the rocker arm 52 carries 15 a pawl 58 normally held in its active position by a spring 59, and the ratchet wheel 34 has secured to the side thereof a lug 60 carrying a few teeth, two being shown in the present instance of the invention. Pivotally mounted at 61 on the pawl 58, which may be denominated the "lazy" pawl, is the active pawl 62 which normally engages the ratchet teeth of the wheel 34. The idle end portion 63 of the active pawl is connected by a link 64 to the inactive end portion of the detent at 65, the construction being such that when the detent 40 is moved by the trip to release the feeler, the active pawl 62 will be thrown out of action, and 20 since the toothed lug 60 is then in a position to be engaged by the lazy pawl 58, the ratchet will be stepped along sufficiently far to permit the trip lug 45 to pass out of engagement with the projection 46 of the 25 detent and will then become inactive, that is, the ratchet wheel 34 will be no longer actuated by the lazy pawl during its reciprocating movement, so that the ratchet 30 34 will dwell or become inoperative and remain at rest. At such time the projection 46 on the detent is above or opposite of the recess 66 between the cam 50 and the trip lug 45 and will be ready to trip into 35 said recess when the feeler is moved sufficiently frontward to permit the spring 47 to move the detent into its holding position, as indicated in Fig. 2. Should the feeler detect a condition approaching exhaustion 40 of the filling in the shuttle on a detecting beat following the release of the feeler as described, it will not be moved frontwardly sufficiently far to enable the active end portion 42 of the detent to move behind the 45 collar 41 on the feeler, but the active end 50 42 of the detent will then rest upon the under surface of the collar 41 and the trip wheel or ratchet 34 will remain at rest. The feeler will then remain in active operation until the filling becomes substantially exhausted, whereupon it will cause replenishment of the filling in a manner well understood. After such replenishment on a detecting beat the feeler will be moved frontwardly by a working supply of filling 55 and the active end portion 42 of the detent

will then rise into holding engagement behind the collar 41 on the feeler. This movement of the detent 40 into active position releases the active pawl 62 to the performance of its function, and the ratchet wheel 70 will start into operation from its initial stopping position, so that after replenishment of the filling the feeler will commence its period of inactivity, which will be of the same length as any other period of inactivity of the feeler. In other words, should the trip mechanism remain in action when the feeler is in operation during the active period with a near approach to substantial exhaustion of the filling, the first period 75 of inactivity of the feeler would be relatively short as compared with other periods of activity, but by suspending or interrupting the operation of the trip mechanism during an active period of the feeler 80 when it detects a near approach to substantial exhaustion, the several periods of inactivity of the feeler are rendered equal, and unnecessary operation or release of the 85 feeler following replenishment is avoided. 90

What is claimed is:

1. In an intermittent feeler mechanism for looms, the combination of a feeler to detect the condition of the filling in the shuttle, a device for holding the feeler in a frontward position during its periods of inactivity, a trip mechanism for freeing the feeler at intervals, and means for stopping the operation of the trip mechanism during an active period of the feeler that the 95 periods of inactivity of the feeler may be equalized.

2. In an intermittent feeler mechanism for looms, the combination of a feeler having periods of activity and inactivity during weaving with the same supply of filling in the shuttle, a trip mechanism for freeing the feeler at intervals that it may move to feeling position, and means for stopping the operation of the trip mechanism when the feeler detects a near approach to filling exhaustion during an active period of the feeler to equalize the periods of inactivity of the feeler. 100

3. In an intermittent feeler mechanism for looms, the combination of a feeler having periods of activity and inactivity during weaving with the same supply of filling in the shuttle, a trip mechanism for freeing the feeler at intervals that it may move to feeling position, means for operating the trip mechanism, and means for interrupting the effective operation of the trip mechanism operating means when the feeler detects a near approach to filling exhaustion during an active period of the feeler that the inactivity periods of the feeler may be equalized. 115

4. In an intermittent feeler mechanism for looms, the combination of a feeler hav-

ing periods of activity and inactivity during weaving with the same supply of filling in the shuttle, a device for holding the feeler in an inoperative position when it has been 5 moved forwardly by a working supply of filling on a detecting beat, mechanism for freeing the feeler at intervals to its periods of activity, and means for stopping the operation of said freeing mechanism when the 10 feeler detects a near approach to substantial exhaustion of the filling.

5. In an intermittent feeler mechanism for looms, the combination of a feeler having periods of activity and inactivity, a 15 device for rendering the feeler inoperative during its periods of inactivity, means actuated from a going part of the loom for freeing the feeler at intervals, and mechanism for stopping the operation of said means during 20 an active period of the feeler when the filling has approached a condition nearing substantial exhaustion until the feeler is again moved forwardly by a working supply of filling that the periods of inactivity 25 of the feeler may be equalized.

6. In an intermittent feeler mechanism for looms, the combination of a feeler, a device for holding the feeler in a forward position during its periods of inactivity, operating 30 mechanism for freeing the feeler at intervals that it may have periods of activity and inactivity, and means for stopping the operation of said mechanism during an active period of the feeler that the inactive 35 periods of the feeler may be equalized.

7. In an intermittent feeler mechanism for looms, the combination of a feeler, a device for moving and holding the feeler in a forward position during its periods of inactivity, operating mechanism for freeing 40 the feeler at intervals that it may have periods of activity and inactivity, and means for stopping the operation of said mechanism during an active period of the feeler 45 that the inactive periods of the feeler may be equal.

8. In an intermittent feeler mechanism for looms, the combination of a feeler, means for holding the feeler in a forward inoperative position during its periods of inactivity, a trip for freeing the feeler from 50 said means at intervals that it may move to a feeling position, a step-by-step mechanism for operating said trip, and means for stopping the effective operation of said step-by-step mechanism during an active period 55 of the feeler that the inactive periods may be equalized.

9. In a feeler mechanism for looms, the 60 combination of a feeler, a device for holding the feeler in a forward position beyond the reach of the filling on detecting beats, a trip for freeing the feeler from said device, means for operating the trip 65 to free the feeler, and mechanism for stop-

ping the operation of the trip operating means during an active period of the feeler.

10. In a feeler mechanism for looms, the combination of a feeler, a device for holding the feeler in a forward position beyond the reach of the filling on detecting beats, a trip for freeing the feeler from said device, ratchet and pawl mechanism for operating the trip that the feeler may have 70 periods of activity and inactivity, and means 75 for rendering the ratchet and pawl mechanism ineffectual during an active period of the feeler.

11. In a feeler mechanism for looms, the combination of a feeler having periods of activity and inactivity, a detent for holding the feeler during its periods of inactivity, a trip device for freeing the feeler from the 80 detent at intervals, a ratchet and pawl mechanism for operating the trip device, and a cam acting through the detent for moving the feeler to a position beyond the reach of the filling where it is held during its 85 periods of inactivity.

12. In a feeler mechanism for looms, the combination of a feeler having periods of activity and inactivity, a detent for holding the feeler during its periods of inactivity, a trip device for freeing the feeler from the 90 detent at intervals, a trip wheel movable in a plane extending transversely to the feeler movement, means for actuating the trip wheel, and a cam acting during movement of the trip wheel for withdrawing the feeler 95 beyond the reach of the filling.

13. In an intermittent feeler mechanism for looms, the combination of a feeler, a device for holding the feeler in inoperative position during its periods of inactivity, a trip for freeing the feeler from said device 100 at intervals, a trip wheel for actuating the trip, and a part carried by the trip wheel for moving the feeler to and holding it in a position beyond the reach of the filling during 105 its periods of inactivity.

14. In a feeler mechanism for looms, the combination of a feeler, a detent mounted for pivotal movement transversely of the feeler and for rocking movement towards and from the front of the loom, means normally acting to hold the detent with its active end towards the rear of the loom, a detent trip mechanism, means movable by the trip mechanism for swinging the active end of the detent forwardly, and means controlled by the detent for stopping movement of the trip mechanism during an active period of the feeler.

15. In a feeler mechanism for looms, the combination of a feeler, a device for holding the feeler in a forward position during its periods of inactivity, a trip wheel, a cam carried by the trip wheel for engagement by 115 said device for moving the feeler forwardly, and means controlled by said device 120 125

for suspending the movement of the trip wheel during an active period of the feeler.

16. In a feeler mechanism for looms, the combination of a feeler, a device for holding the feeler in a frontward position during its periods of inactivity, a trip wheel, a cam having an interrupted portion and carried by the trip wheel for engagement by said device for moving the feeler frontwardly, and means controlled by said device for suspending the movement of the trip wheel during an active period of the feeler.

17. In a feeler mechanism for looms, the combination of a feeler, a detent for engagement by the feeler, a trip wheel having a cam for holding the detent in a frontward position when engaged by the feeler, means for actuating the trip wheel to periodically release the feeler, and means controlled from the detent for stopping movement of the trip wheel during the active period of the feeler that the inactive periods may be equalized.

18. In a feeler mechanism for looms, the combination of a feeler having periods of activity and inactivity during weaving with the same supply of filling in the shuttle, a detent for holding the feeler in a frontward position during its periods of inactivity and

mounted to turn about a vertical and a horizontal axis, means for turning the detent about its horizontal axis to free the feeler, and other means for turning the detent about its vertical axis to cause the feeler engaging portion of the detent to be moved rearwardly as it frees the feeler and when reengaged by the feeler to move the feeler to a frontward position beyond the reach of the filling.

19. In a feeler mechanism for looms, the combination of a feeler, a detent extending transversely of the path of movement of the feeler and mounted to swing about a horizontal axis to engage and release the feeler and thereafter about a vertical axis to withdraw the feeler to a frontward position, means for swinging the detent about its horizontal axis to release the feeler at intervals, and other means for swinging the detent about its vertical axis to cause the feeler engaging portion of the detent to be moved rearwardly as it frees the feeler and when engaged with the feeler to withdraw the feeler to a frontward position.

In testimony whereof, I have signed my 55 name to this specification.

ALONZO E. RHOADES.
